UNITED STATES PATENT OFFICE.

SAMUEL PARADIS, OF KANSAS CITY, MISSOURI.

MAGAZINE-FIREARM.

SPECIFICATION forming part of Letters Patent No. 699,703, dated May 13, 1902.

Application filed December 13, 1901. Serial No. 85,823. (No model.)

To all whom it may concern:

Be it known that I, SAMUEL PARADIS, a citizen of the United States, residing at Kansas City, in the county of Jackson and State of Missouri, have invented new and useful Improvements in Magazine-Firearms, of which the following is a specification.

My invention relates to magazine-firearms, especially rifles; and the object of my invention is to produce a firearm having a compound magazine composed of a plurality of tubes or bores for cartridges and means for rotating the magazine intermittently to feed cartridges to the action.

15 A further object of my invention is to produce means for preventing the arm from being fired until the action-slide has been fully reciprocated and for preventing the action-slide from being again moved until the arm 20 has been fired.

My invention will now be described with reference to the drawings, in which—

Figure 1 is an irregular section of the receiver, omitting the guard and stock, showing a portion of the magazine with cartridges therein, a shell in the breech, and the action-slide in full back position. Fig. 2 is another irregular section through the receiver, omitting the guard and the magazine, the stock 25 and barrel being broken away, the carrier being partly in section with a cartridge therein, and the action-slide in its forward position. Fig. 3 represents the action-slide detached, partly in central vertical longitudinal section. Fig. 4 is an elevation of the front end of the action-slide. Fig. 5 represents the rear portion of the magazine broken away. Fig. 6 is an elevation of the front end of the magazine, the plugs being removed. 30 Fig. 7 is an elevation of the rear end of the magazine. Fig. 8 is a side elevation of the front end of the magazine, broken away, a portion of the barrel and the magazine-bearing secured to the barrel. Fig. 9 is a front 35 elevation of the breech-bolt. Fig. 10 is a top plan view of the breech-bolt and the extractor secured thereto. Fig. 11 is a rear end elevation of the breech-bolt with the cover attached. Fig. 12 is a bottom plan view of 40 the slide-and-hammer lock. Fig. 13 is a top 45 elevation of the breech-bolt. Fig. 14 is a front end elevation of the carrier. Fig. 15 is a top 50 plan view of the carrier-lifter and the link and lever connected thereto in the position in which they appear in Fig. 2. Fig. 16 is a transverse section through the barrel and the action-slide, omitting the magazine, looking 55 toward the receiver. Fig. 17 is a top plan view of the receiver, omitting the movable parts therein and the carrier-lifter, showing 60 a part of the magazine and a part of the action-slide sleeve broken away. Fig. 18 is a broken-away side elevation of the interior of the receiver, the movable parts being removed.

Referring to Figs. 1, 5, 6, and 7, 1 designates the cartridge-magazine, which is compound, containing a plurality of bores 2, as shown in Figs. 6 and 7. The ends of the magazine are provided with concentric studs 7c 3 4. The stud 3 at the front end of the magazine is mounted rotatably in a bearing-piece 5, rigidly secured to the barrel 6. Stud 4 at the breech end of the magazine is mounted rotatably in a hole 7 in the front wall 8 of the receiver. (See Figs. 1 and 2.) In the partition 8 above said hole 7 is the magazine discharge-hole 10, Figs. 1, 2, and 16, through which the cartridges are pushed by the usual springs (not shown) in the magazine 1. The magazine being rotatably mounted by means of the studs 3 4, each of the bores 2 may be brought into register with the said discharge-hole 10 in the receiver 9. The magazine-bores 2 are filled successively through a feed-hole 85 11 in the partition 8, this hole being shown in Fig. 16 and passes through the right-hand side (not shown) of the receiver 9, so that the magazine is filled in the same manner as a single-bore magazine by pushing the cartridges in through hole 11. The action-slide 15 16 comprises a sleeve 15, which embraces a portion of the magazine 1, and a rearward extension 16, which operates the breech mechanism in the manner described herein-after. Secured within the sleeve portion 15 or integral therewith are two sets of thrower-points 17 and 18. Rigidly secured to the outside of the magazine 1 are two corresponding sets of points 19 and 20. Said points 19 are 100

formed on a collar 13, which is detachably secured on the magazine with a screw 14 or in any preferred manner.

When the gun is assembled, the thrower-points 17 18 lie between the magazine-points 19 and 20, while the latter fill the bore of the action-slide 15 16, which is prevented from rotating by two longitudinal ribs 21 thereon, Fig. 4, which loosely fit alongside the barrel 10 of the gun. Hence when the action-slide 15 16 is reciprocated by the hand of the operator so that the thrower-points 17 18 enter between the magazine-points 19 or 20 the magazine 1 will be intermittently rotated. Said points 15 are all so proportioned that a complete forward-and-back stroke of the action-slide 15 16 is required to register a different bore of the magazine with the discharge-hole 10.

The number of thrower-points and magazine-points in each set is the same as the number of bores 2 in the magazine.

The breech-action will now be described, referring to Figs. 1, 2, and 17 especially. The extension 16 of the action-slide 15 16 closes the bottom of the receiver 9 when the action-slide is back, as shown in Fig. 1. Secured to the upper face of the extension 16 at the rear end thereof is a block 22, termed hereinafter the "carrier-lifter." Pins 23, secured in this block, enter holes 24 in the extension 16, and a screw 25 secures said block thereto. The cartridge-carrier 26 is pivoted at 27. A front elevation of this piece is shown in Fig. 14, in which 28 designates the cylindrical opening 35 for receiving a cartridge. The function of the carrier 26 is to lift each cartridge from the magazine 1 to a position in line with the bore of the barrel 6. The carrier 26 has an inclined lower face 29, and the carrier-lifter 40 22 has a similarly inclined upper face. When the carrier-lifter 22 is drawn forward by movement of the action-slide 15 16, the inclined face of the carrier-lifter 22 impinges upon the face 29 of the carrier 26, and thereby 45 raises the carrier from the position shown in Fig. 1 to that shown in Fig. 2. The breech-bolt 31 is mounted slidably in the top of the receiver 9 by means of a cover-plate 32, secured thereto, the sides of which plate run 50 in grooves 33, cut in the inner sides of the receiver 9. On the top of the breech-bolt 31 is mounted the shell-extractor 34, which is simply a spring having a depending hook at its forward end. The firing-pin 35 (shown 55 in plan and end elevation in Figs. 9, 10, and 11) is mounted in the breech-bolt 31 in the usual manner, it being capable of the slight longitudinal movement necessary to fire the cartridge when struck by the hammer 36. 60 The outline of the front portion of the firing-pin 35 is shown in dotted lines in Fig. 1. The breech-bolt 31 is provided with depending lugs 31', Figs. 1 and 11, between the front and rear pair of which is a swell 37, formed 65 on the end of a lever 38, pivoted at 39. The opposite end of this lever 38 is connected by

a link 40 to the carrier-lifter 22, to which it is secured by a pivot-pin 41. Thus forward motion of the action-slide 15 16 pulls lever 38 around to the position shown in Fig. 2, and 70 said lever forces back the breech-bolt 31 by means of swell 37 engaging lugs 31'. Backward motion of the action-slide throws lever 38 to the position shown in Fig. 1, thereby moving the breech-bolt 31 forward through 75 the carrier 26, pushing the cartridge forward to the position shown in Fig. 1. In this figure a shot is supposed to have been fired, which leaves the empty shell in position to be withdrawn by the extractor 34. The lever 38 80 works in a slot 42 between the twin arms of the carrier 26. (See Fig. 13.) Referring to Fig. 15, lever 38 is provided with two pins 37', which project beyond the sides of the swell 37 for the purpose of engaging the arms 85 of the carrier 26 during their descent, and thus pushing down the carrier as soon as the front end of the breech-bolt has passed the sides of the cartridge-opening 28. The carrier 26 is held in its raised position by frictional engagement with two slight bosses 56 90 56, formed on the inner sides of the receiver 9, as shown in Figs. 17 and 18. The arms of the carrier are made slightly yielding in order to better pass over these bosses. The 95 hammer 36 is pivoted at 43 and impelled by a spring 44.

An important part of my invention is the piece 45, termed hereinafter the "slide-and-hammer lock." This lock or detent is pivotally mounted on a pin 46. When the hammer 36 is at full-cock, as shown in Fig. 2, a notch 47 therein is entered by a heel 48 on the slide-and-hammer lock 45, as shown. The slide-and-hammer lock has a forward extension terminating in a catch 49, which is adapted to engage a notch 51 at the back end of the carrier-lifter 22. The rear face of the carrier-lifter is inclined, as shown, so that when it is pushed back by the action-slide 15 16 said inclined face passes under and raises the catch 49 and moves far enough back to permit said catch to drop into the notch 51. The catch 49 is urged downwardly by a spring 52, engaging the toe of the slide-and-hammer lock 45. Thus when the hammer 36 is at half or full cock, with the action-slide 15 16 clear back, the catch 49 is in the notch 51, and thereby prevents the action-slide from being "pumped" until the shot is fired. Firing 120 the shot brings the hammer forward, as shown in Fig. 1, which causes a cam portion 36' of the hammer to move back and depress the heel of the slide-and-hammer lock 45, thus lifting the catch 49 out of its notch 51 and 125 permitting the action-slide to be pumped. When the action-slide is in forward position, as shown in Fig. 2, the heel of the slide-and-hammer lock 45 is free to enter the notch 47 in the hammer, which it does, and thereby 130 prevents the gun from being fired until the return movement of the action-slide pushes

the carrier-lifter 22 under the catch 49, and thereby releases the heel 48 from the hammer.

The slide-and-hammer lock 45 is slotted out, as shown in Fig. 12, to receive the trigger 53, which is pivoted on the pin 46. 54 designates the trigger-spring.

The cycle of operations of this gun is as follows: Cartridges are placed in each bore of the magazine 1 through the feed-hole 11.

10 One cartridge lies in the carrier 26, having been pushed thereinto by one of the long spiral springs in the magazine. The action-slide 15 16 is reciprocated once—that is, moved forward and then back. The first of these 15 movements raises the carrier 26 and cartridge to the position shown in Fig. 2. The second of said movements moves the breech-bolt 31 forward and then lowers the carrier 26. This second movement also completes 20 the partial rotation of the magazine 1, so that the carrier 26 receives another cartridge. The trigger 53 is pulled, the hammer 36 strikes the firing-pin 35, which fires the cartridge. The extractor-hook 34, which was passed over 25 the rim of the cartridge by the forward motion of the bolt 31, is retracted by the next forward motion of the action-slide, extracts the cartridge, which is then thrown up and out of the gun by the quick ascent of the carrier 26. The 30 action is now in the position shown in Fig. 2. The action-slide is now pulled back, and the arm is again ready to fire. The points 17, 18, 19, and 20 of the magazine and the action-slide may be so shaped as to bring the magazine-bore into register with the carrier 26 either before or after a shot is fired in the barrel.

From the preceding description it will be evident that I have produced a magazine-rifle 40 of very large capacity, compact and simple in construction, and containing new and reliable devices for preventing the arm from being fired until the carrier is in lowered position and for preventing the action-slide 45 from being operated until a shot has been fired.

Having now fully described my invention, what I claim as new, and desire to secure by Letters Patent of the United States, is—

50 1. In a firearm, a compound magazine mounted rotatably below the barrel, two sets of pointed projections secured on the magazine, said projections in one set being pointed toward the projections in the other set, 55 and the number of said projections in each set corresponding to the number of bores or tubes in the magazine, an action-slide comprising a sleeve embracing the portion of the magazine having said projections thereon, 60 said sleeve being movable longitudinally on the magazine but not rotatable, two sets of pointed projections secured within said sleeve, the projections in said sets pointing oppositely, and lying between the aforesaid 65 pointed projections on the magazine, the projections in said sleeve being so arranged that

when said sleeve is moved in one direction over the magazine, one set of projections in said sleeve will engage the corresponding set of projections on the magazine, and will 70 thereby partially rotate the magazine, and when said sleeve is moved in the opposite direction over the magazine, the other set of projections in said sleeve will engage the other set of projections on the magazine, and will 75 thereby further rotate the magazine; substantially as and for the purpose described.

2. In a firearm, an action-slide having a rearward extension, a block secured to said action-slide, a notch 51 in the upper face of 80 said block, a hammer having a cam portion 36', a slide-lock consisting of a forwardly-extending catch, mounted pivotally below the hammer, said catch being adapted to engage said notch in said block, and an extension of 85 said catch arranged to be depressed by said cam portion of the hammer when the hammer is closed, thereby holding said catch disengaged from said notch to permit said action-slide to be moved forward; substantially 90 as described.

3. In a firearm, an action-slide having a rearward extension, a block secured to said action-slide, said block having an inclined rear face, a notch 51 in the upper face of said 95 block, a hammer having a cam portion 36', a slide-and-hammer lock comprising a forwardly-extending catch and a rearwardly-extending portion having a heel or detent 48 thereon, a notch 47 in the rear face of said 100 cam portion of the hammer, adapted to be entered by said heel or detent when the hammer is cocked, a pivot-pin extending through said slide-and-hammer lock between said catch and said rearwardly-extending portion; 105 the action of said parts being that when said slide and block are moved back, the inclined rear face of said block will raise said catch and thereby disengage said detent 48 from said notch 47, thereby permitting the hammer 110 to fall when released by the trigger; substantially as described.

4. In a magazine-firearm, the combination, with the receiver, of an action-slide having a rearward extension, a block secured thereto, 115 said block having an inclined front face, a cartridge-opening 10 in the front wall of the receiver, a carrier having a cartridge-pocket 28 and an inclined lower face 29, a lever, a link connecting the lower end of said lever 120 to said block, said lever lying partly between the arms of said carrier, and pins projecting from the upper end of said lever, whereby the forward motion of said block raises said carrier to register with the bore of the barrel, 125 while the backward motion of said block moves the upper end of said lever obliquely downwardly, causing said pins to follow the arms of said carrier down until the cartridge-pocket in the receiver registers with said 130 cartridge-opening in the front wall of the receiver; substantially as described.

5. In a magazine-firearm, an action-slide having a rearward extension, a block secured to said extension, a link pivotally connected to said block, a breech-bolt provided with 5 depending lugs, arranged to form a vertical slot therebetween, and a lever having its upper end extending into said slot and its other end pivotally connected to said link, whereby movement of said slide in either direction

will move said breech-bolt in the opposite direction, substantially as described.

In testimony whereof I affix my signature in the presence of two witnesses.

SAMUEL PARADIS.
